US0D1043760S

(12) **United States Design Patent** (10) **Patent No.:** **US D1,043,760 S**
(45) **Date of Patent:** **** Sep. 24, 2024**

(54) **AIR COMPRESSOR**

(71) Applicants: **Wen-San Chou**, Tainan (TW);
Cheng-Hsien Chou, Tainan (TW)

(72) Inventors: **Wen-San Chou**, Tainan (TW);
Cheng-Hsien Chou, Tainan (TW)

(**) Term: **15 Years**

(21) Appl. No.: **29/836,507**

(22) Filed: **Apr. 27, 2022**

(30) **Foreign Application Priority Data**

Nov. 10, 2021 (TW) 110306101

(51) **LOC (14) Cl.** **15-02**

(52) **U.S. Cl.**

USPC **D15/9; D15/7**

(57) **CLAIM**

The ornamental design for an air compressor, as shown.

DESCRIPTION

FIG. 1 is a first perspective view of an air compressor showing my new design thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof, and

FIG. 8 is a second perspective view of an air compressor showing my new design thereof; and,

FIG. 9 is a third perspective view of an air compressor showing my new design thereof.

The broken lines shown in the drawings represent portions of the air compressor that form no part of the claimed design.

1 Claim, 9 Drawing Sheets
